(57) **CLAIM**

The ornamental design for a radio frequency antenna as
shown and described.

DESCRIPTION

This application claims priority to U.S. Application Nos. 62/839,125, 62/839,131, 62/842,816, respectively filed Apr. 26, 2019, Apr. 26, 2019 and May 3, 2019. Priority is claimed to any application(s) identified in the specification and/or ADS, and the contents thereof are incorporated by reference in their entireties into this application as if fully set forth herein, and to the maximum extent allowed by applicable law.

The FIGURE is a right front perspective view of the claimed
design for a radio frequency antenna.

The broken lines immediately adjacent to the claimed area
depict boundaries of the claimed design and form no part
thereof.

1 Claim, 1 Drawing Sheet
